DEVICE FOR REMOVING INVESTMENTS
FROM SECTIONAL DENTAL FLASKSEdmond J. Franwick, Buffalo, N. Y., assignor to
Hanau Engineering Company, Inc., Buffalo,
N. Y., a corporation of New York

Application June 26, 1939, Serial No. 281,183

9 Claims. (Cl. 18—33)

My invention relates to a device for removing investments from dental flasks. Heretofore, after investing a case with plaster of Paris and curing the case in a dental flask, it was necessary to gouge out the plaster from the flask and at times subject the investment to severe blows by means of a hammer or other instrument in order to loosen the investment from the flask. This was particularly true due to the fact that the inner surface of the flask is usually more or less rough or irregular, and also because of the fact that the proper tapers had not been provided.

Although flasks heretofore used have been made in sections, they could not be easily separated for reasons stated, and their construction made it exceedingly difficult to separate the sections because of the bonding of the investment to the sections.

One of the objects of my invention is to provide what I term an ejector for use in connection with flasks, the flask proper being arranged within a suitable frame or support and means provided to easily loosen sections of the flask so as to permit of a convenient separation, allowing the investment to be withdrawn as a complete unit.

Another object of my invention is to provide an ejector frame or support for removing investments from flasks to be used in association with prying elements, and to equip said frame or support with means to enable said prying elements to be fulcrumed thereon so as to exert pressure against parts of the flask for the purpose of loosening the investment from the flask.

A further object of my invention is to provide the ejector frame or support with openings so positioned with reference to depressions or notches formed in the flask that upon inserting prying elements through said openings and entering the inner ends thereof in said depressions or notches, pressure applied to said prying elements, while using one of the walls of each of said openings as a fulcrum point, will quickly loosen the sections of the flask from each other and from the investment therein while both are retained within the frame or support.

A still further object of my invention is to so construct the flask that the sections thereof can be easily removed from the investment.

With the above and other objects in view, my invention consists in associating a sectional flask with my improved ejector means, which when brought into use will quickly and efficiently separate the sections of the flasks so as to permit of removing the investment therefrom as a complete unit.

The invention also consists in associating a sectional flask with a frame or support in which said flask is held and which frame or support is adapted to have associated therewith means for coaction therewith and with the flask to cause separation of the sections of the flask and thereby separate the investment in the flask from the sections thereof.

The invention further consists in the novel features of construction and in the arrangement and combination of parts to be hereinafter described and more particularly pointed out in the subjoined claims.

In the drawings—

15 Fig. 1 is a side elevation of my improved ejector type flask, the flask being shown inverted in the frame or support and having the upper section or cover of the flask removed.

Fig. 2 is a rear elevation of the flask and the frame or support.

Fig. 3 is a plan view of the same.

Fig. 4 is a perspective view of the frame or support in which the flask is to be retained when the upper section or cover of the same is removed.

25 Fig. 5 is a vertical longitudinal section taken on line 5—5, Fig. 2.

Fig. 6 is a horizontal section taken on line 6—6, Fig. 1, looking up.

Fig. 7 is a vertical section through a portion of the flask taken on line 7—7, Fig. 9, a portion of the investment being shown.

Fig. 8 is a vertical section taken on line 8—8, Fig. 9 showing the investment in the flask preparatory to curing the case.

35 Fig. 9 is a perspective view of the flask proper.

Having reference to the drawings in detail, 10 designates the ejector frame or support utilized to receive therein a portion of the sectional flask 11.

40 This frame or support comprises a base 12 having an elevated portion 13 conforming somewhat to the outline of the flask, but preferably smaller than the latter, and rising from the base are two opposite uprights or posts 14 connected by a cross bar 15 at a distance spaced from the elevated portion 13 of the base somewhat greater than the height of the flask portion to be used in connection with this frame or support. Formed medially on said cross bar is an enlargement or head 16 from which rises a boss 17. The enlargement or head 16 is made hollow on its underside, as at 18, to receive a pressure element 19 in the form of a disk swiveled to the lower end of a pressure screw 20 threaded through the boss 17 and the upper wall of the enlargement or head 16.

45 For conveniently operating the pressure

screw, it is provided with a knurled head 21 at its upper end.

Extending from diametrically opposite points of the enlargement or head 16 and the boss 17 and arranged at right angles to the cross or connecting bar 15 are arms 22 having at their outer ends upstanding portions 23 and these arms are webbed to strengthen the same and give them a symmetrical appearance. The upstanding portions 23 terminate in the plane of the upper ends of the uprights or posts 14, and when the frame or support is reversed, as may be found desirable at times, said upright portions and uprights or posts serve as legs for the device.

The elevated portion 13 of the base is provided with screw holes 24 (one only being shown in Fig. 4) by means of which the frame or support can be conveniently fastened to a table or other foundation. In the uprights or posts 14 openings 25 are arranged, the purpose of which will appear hereinafter. The ejector frame or support 10 with its several integral and associated parts may be termed holding means or supporting means in its broadest sense, although more specifically it may be termed an ejector or flask-stripping frame.

The flask proper is formed in three sections; one 26, which I term the lower section or member; the second 27, referred to as an intermediate section or member; and the third 28, which may be called the upper section or member, but which in reality is a comparatively flat member and may be more particularly referred to as the cover of the flask. The flask may be described as parti-circular in formation in that it has almost a cylindrical form, and at one side it is provided with a substantially straight-lined heel portion 29 which may be said to cut off a sector of a cylinder. Each of the sections has lugs 30 at the points where the straight-lined portion approaches the parti-cylindrical portion of the perimeter of the flask. The parting lines of the sections or members are designated by the numerals 31, 32, and the intermediate section or member 27 of the flask is provided at these parting lines, or more particularly at its upper and lower edges axially of the lugs 30 with dowel pins 33, 34. These dowel pins are secured in the lugs 30 of the intermediate section and their upper ends project from the upper edge of said section, said projecting ends being comparatively short, preferably a trifle less in length than the thickness of the upper section or member 28. These dowel pins also project from the lower edge of said intermediate section and these projecting ends are comparatively long. The upper ends of the dowel pins 33 and 34 enter dowel openings 35 in the upper section or cover, while the lower ends thereof enter dowel openings 36 in the lugs of the lower section or member. In this manner the sections are caused to register so that the exterior of the flask is perfectly flush at the parting lines 31 and 32 and the interior surfaces of the walls of the sections or members are preferably alined at all points within the flask. The intermediate section or member 27 has the inner surfaces of its walls flared downwardly, as at 37, while the lower section or member 26 has its inner surfaces flared upwardly, as at 38.

To assure easy and perfect assembly of the flask sections and to direct the ends of the dowel pins 33 and 34 properly into the dowel openings 35 and 36 of the upper and lower sections, the extremities of these dowel pins are tapered as shown at 33^a and 34^a, the tapers 33^a being at the

upper end of the dowel pins and the tapers 34^a at the lower ends thereof. The major portions of the dowel pins 33 and 34 and the dowel openings receiving the projecting ends thereof are cylindrical. The lower ends, however, of the dowel openings 35 are flared, as at 35^a, while the upper ends of the dowel openings 36 are flared, as at 36^a. The tapers at the upper ends of the dowel pins are comparatively short, and the cylindrical portions of said pins adjacent said tapers rise above the flared lower portions of the dowel openings 35 and fit snugly within the cylindrical upper portions of said dowel openings. The tapers at the lower ends of the dowel pins are somewhat longer, due to the fact that the dowel openings in the lugs of the lower section of the flask are comparatively long, but the cylindrical portions of said pins adjacent said tapers extend beneath the flared portions of the dowel openings 36 and fit snugly within the cylindrical lower portions of said dowel openings. It will be understood, therefore, that by tapering the extremities of the dowel pins and providing the dowel openings 35 and 36 with flared portions, the pins will be easily guided into their respective receiving openings in the upper and lower sections of the flask, and assurance will be had of a perfect alinement of the flask sections.

The flask is shown in its normal position in Fig. 9 of the drawings, and when preparing the investment it is so positioned, the model or case, designated by the numeral 39, is placed within the lower section of the flask after separating the sections thereof. This model or case comprises the usual stone mounting 40 on which is built a wax ridge 41 having portions of artificial teeth 42 embedded therein. The stone or other mounting is molded or formed to a thickness conforming approximately to the height of the surrounding walls of the lower section so that its upper surface is in horizontal alinement with the upper edges of said walls. The wax ridge and the teeth, therefore, project above the plane of said upper edges. The space between said walls and the stone or other mounting of the model or case is then filled with plaster of Paris in plastic form, as shown at 43, or some other medium possessing similar qualities, the plastic mass being leveled off even with the upper edges of the said surrounding walls and the mounting. The upper surface of this plastic mass and that of the stone mounting 40 is then coated with a separating medium, such as soapstone or other like material, after which the intermediate section or member 27 is seated on the lower section or member. This intermediate section or member is then filled with plaster of Paris in plastic form or some other similar material, as shown at 44, completely covering the model or case. The plaster of Paris is then leveled off even with the upper edge of said intermediate section or member. These two plastic masses, one within the lower section and the other within the intermediate section of the flask, form the investment for the model or case. The upper section or cover is then placed upon the intermediate section and over the second mass of plaster of Paris within the intermediate section, and it has one or more holes 45 formed therethrough into which a small quantity of plaster of Paris in plastic form is to be placed so as to become bonded with the plastic material within the intermediate section of the flask. To assure a good bonding at these points the walls of said holes are flared outwardly and are to be

filled in before the plastic material within the intermediate section becomes set.

Up to this point there has been provided an investment with a parting line 46 between the two portions 43, 44 of the investment, the parting line of the investment of course being coincident with the parting line 32 between the intermediate and lower sections of the flask.

The flask thus prepared is placed in boiling water, at which time the wax ridges 41 become fluid and the wax oozes out, at least in part, through the parting line 46 of the investment and the parting line 32 of the flask. The flask is then opened and the opposing surfaces of the two investment portions 43 and 44, as well as the upper surface of the stone mounting 40, are then washed with hot water so that all wax and the separating medium previously employed are disposed of. The teeth will now be held in position by the investment portion 44 within the intermediate section. The wax originally within this investment portion 44 having been disposed of, a groove is formed of the exact formation which the wax ridges originally had, the teeth projecting with their root portions downwardly into said groove. This groove is then packed with a vulcanizable or curable material, and the intermediate section of the flask having the investment portion 44 is again placed upon the lower section with its investment portion 43, the registering dowels on the flask bringing the two sections together in the same relation as they had when the investment was being prepared. The upper section or cover is then placed upon the intermediate section and the case cured in any approved manner.

While the method of procedure thus far described forms no portion of my invention, it is believed necessary to describe such procedure in order to have a clear understanding of the use and advantages of my invention.

As hereinbefore stated, it has been a difficult matter to remove the investment from the flask, and in gouging out the plaster material from the flask or subjecting the investment to blows by the use of a hammer or other instrument in order to break or shatter the same while within the flask, the denture thus created from the model or case often becomes broken, with the result that the entire operation steps referred to must again be repeated.

By the use of my ejector or flask-stripping frame in association with suitable flask-removing means, separation of the flask from the investment can be easily effected. With this end in view the upper section or cover 28 is removed from the flask, and the remainder of the flask with the investment therein is reversed and positioned within the frame, or flask holder as it may be termed. So positioned, it is supported on the elevated portion 13 of the base, the plaster of Paris investment only being in contact with said elevated portion, as clearly shown in Fig. 5. The bottom wall of the lower section therefore is at the top, as clearly shown in said figure. This bottom wall is provided with a large opening 47, preferably circular, counterbored inwardly to form an inwardly opening shoulder 48, said opening being closed by a holding element 49 whose edge is rabbetted to fit said counterbored opening and thus permit movement of the lower section outwardly or upwardly while retaining said holding element against the investment and the stone or other mounting provided for the denture.

With the flask so positioned, the pressure element 19 is held tightly against what is now the top of the inverted portion of the flask and more particularly against the holding element 49 by manipulating the pressure screw 20. The flask minus its top section or cover is now firmly clamped within the frame or support with the investment having the denture embedded therein, as clearly shown in Fig. 5. The lower section 26 of the flask is provided at its upper edge with notches or depressions 50, one notch being preferably arranged at the heel portion of the flask and the other at a point diametrically opposite so that these notches or depressions are in line or substantially in line with the openings 25 in the uprights or posts 14. It is of course understood that the notches or depressions could be as well formed in the lower edges of the intermediate section 27. The uprights or posts are provided with lateral extensions 51 at opposite edges in line with the openings 25 therein, which not only provide added strength for these uprights or posts where weakened by such openings, but the extensions of one of said posts are utilized to properly position the flask within the frame or support, since the lugs 30 of the flask are intended to be positioned against the inner sides of said last-mentioned extensions, as best shown in Fig. 3. So positioned, the investment only lies in contact with the elevated portion 13 of the base, while the walls of said intermediate section are located outside the area of said elevated portion, for a purpose to presently appear.

52 designate prying elements in the form of flat bars which are inserted through the openings 25 in the uprights or posts 14 and have their inner ends reduced in thickness, as at 53, so as to enter the notches or depressions 50 in the lower section 26 of the flask, as clearly shown in Fig. 5. With the prying elements or bars 52 so positioned and the holding element 49 forced against the investment by the pressure screw 20, it is only necessary to exert pressure downwardly on the prying elements or bars while utilizing the lower walls of the openings 25 in the uprights or posts as fulcrum points for said prying elements or bars to cause the lower section of the flask to be moved or stripped upwardly from the investment therein to the position shown in dotted lines 54 in said figure, said movement being permitted, due to the fact that the inner surface of the peripheral wall of said lower section is flared upwardly, as considered when the flask is in the normal position shown in Fig. 9. After the lower section 26 is stripped from the investment, it is only necessary to force the prying elements or bars 52 upwardly, whereupon the intermediate section 27 is forced downwardly within the frame to assume the position shown in dotted lines 55 in Fig. 5, this being permitted due to the fact that the inner surface of the peripheral wall of said intermediate section is flared downwardly when the flask is in normal position. It will thus be seen that although the investment becomes firmly bonded to the walls of the flask during the act of curing the case or denture, with my improved invention the flask can be quickly and easily separated therefrom. Upon loosening the pressure screw and loosely repositioning the flask sections over the investment, the flask with the investment loosely therein can be easily withdrawn from the frame or support, after which the investment can be withdrawn from the flask and broken or cut away without any possibility of breaking the denture therein, the latter being

easily stripped from the stone mounting so that after a thorough cleansing, it is ready for fitting within the mouth of the patient.

In some instances it may be found desirable to invert the frame or support so that it rests upon the upper ends of the uprights or posts 14 and upon the upstanding portions 23 of the arms 22. At such times both uprights or supports and the upstanding portions 23 serve as legs, and when so positioned the sections 26 and 27 can be stripped from the investment by exerting pressure successively in opposite directions on the prying elements or bars 52. This reversal of the frame or support may by some be considered desirable, particularly when the frame or support is not fastened to a table or other foundation.

It will be apparent that the frame or support with the prying elements or bars provide a convenient stripping device for stripping the sections of the flask from the investment and that the investment can be broken or cut away from the denture while free of any surrounding object, thus materially minimizing the chances of injuring the denture in the act of removing it from the investment; at the same time enabling such removal within a small fraction of the time and with less care than is now found necessary under present day methods.

Where in the claims reference is made to a "flask" or "sectional flask," it is intended to include a flask in which an investment is entirely enclosed, or in which a portion of the flask is removed and a portion of the investment exposed.

Having thus described my invention, what I claim is:

1. A device for removing investments from sectional dental flasks, comprising holding means to engage and hold the investment immovably therein while within said flask, and means provided on said holding means to permit a pry to be fulcrumed thereon for separating the sections of the flask and freeing the investment therefrom while retained immovably in said holding means.

2. A device for removing investments from sectional dental flasks, comprising supporting means provided with means to retain the investment immovably within said supporting means while within said flask and with means to permit separation of the sections of said flask under prying action of suitable elements fulcrumed on said supporting means while said investment is immovably retained within the latter.

3. A device for removing investments from sectional dental flasks, comprising supporting means to immovably clamp the investment within the flask while allowing clearance space for movement of the sections of said flask, and means embodied in said supporting means serving as fulcrum points on which prying elements are adapted to be fulcrumed for loosening the sections of said flask from said immovably clamped investment and for moving portions of said sections into said clearance space.

4. A device for removing investments from sectional dental flasks, comprising supporting means for said flask including elements at opposite sides of said flask, means to clamp said investment at the top and bottom within said supporting means while retaining said flask sections in unclamped condition, said elements being provided with means for association therewith of prying means utilizing said elements to provide ful-

crums therefor, said prying means being adapted to engage the sections of said flask and exert force thereagainst to strip the same from said investment while the latter is clamped.

5. A device for removing investments from sectional dental flasks, comprising a stripper frame for a flask having a base upon which the investment within said flask rests and an upright rising from said base provided with a bearing point adapted for association with a prying element designed to engage the sections of said flask while utilizing said bearing point as a fulcrum to exert force against either or both sections of said flask and strip at least one of said sections from said investment.

6. A device for removing an investment from a sectional flask separable along a horizontal plane and having a bottom for one section provided with a holding element from which the remainder of said section is removable, comprising a stripper frame having a base and uprights rising from said base and positioned at opposite sides of said flask, and a clamping element above said flask bearing against said holding element to retain the same and said investment in fixed position on said base, said uprights having means to serve as fulcrums for prying elements adapted for engagement with the sections of said flask to strip the same from said investment while retaining said holding element against the latter.

7. A device for removing an investment from a sectional flask separable along a horizontal plane and having a bottom for one section provided with a holding element from which the remainder of said section is removable, comprising a stripper frame having a base, uprights rising from said base at opposite sides of said flask and provided with openings, a cross bar connecting said uprights and extending across the flask with clearance space between the latter and said cross bar and a pressure device carried by said cross bar and exerting pressure downwardly against said holding element whereby said investment is clamped between said holding element and said base, said openings being adapted to have prying bars exerted therethrough and fulcrumed therein to engage a section of said flask and strip the major portion of the same from said investment and to separate said portion from said holding element while moving said portion upwardly into said clearance space.

8. A device for removing an investment from a sectional dental flask having a lower section provided with a bottom equipped with an investment-holding element from which the remainder of said section is removable, and a second section adjoining said bottom section and in contact therewith edge to edge, comprising a stripper frame in which said flask is placed in inverted position, said frame having a base with an elevated portion of smaller dimension than the interior cross-sectional dimension of said flask against which the investment in said flask bears, two uprights rising from said base at opposite sides of said flask, each having an opening therein, a cross bar connecting said uprights in a plane above said flask and extending across the latter, and a holding device including a pressure screw carried by said cross bar and bearing against said investment-holding element, the walls of said openings serving as fulcrums for prying elements adapted to pry the lower section of said flask upward away from said investment and from said investment-holding element and the upper

section downward around said elevated portion and free of said investment.

9. A device for removing investments from sectional dental flasks, comprising holding means engaging the investment at the top and bottom to immovably retain the same and including means

to fulcrum a prying element thereon for prying the sections of the flask apart while said investment is immovably retained within said holding means.
